POCKETLESS DISPLAY PEN
Warren Shea, Jersey City, N.J., assignor to Radiant Pen Corp., Kenilworth, N.J.
Filed Mar. 22, 1961, Ser. No. 97,632
1 Claim. (Cl. 40—334)

My invention relates to a ball point pen, and more particularly to a pen provided with internal means for displaying printed or decorative material.

Display pens are generally employed for carrying an advertising message. In some good constructions, the appearance of the pen can be changed by providing a new color or decoration.

Hitherto such display material could only be provided by printing or decorating the outside barrel of the pen, or by completing changing the construction of the pen barrel of the pen so as to provide a pocket for the insertion of the display material. Printing on the pen barrel has been found to be undesirable because of the constant wear on the surface, which gradually causes illegibility. Where pockets are employed, expensive molding and assembly charges are involved which greatly increase the cost of the pen.

The principal object of the invention is to provide a display pen which does not cost substantially more to make and assemble than the conventional pen.

Other objects are to provide a display pen with a minimum number of parts, including a conventional pen barrel containing easily changed display material, and to provide a display pen that is adapted to be manufactured using mass production methods.

I accomplish these and other objects and obtain my new results as will be apparent from a consideration of the display pen described in the following specification, particularly pointed out in the claim, and illustrated in the accompanying drawing in which:

FIGURE 1 is an exploded view of my novel display pen embodying the invention; and

FIGURE 2 is a fragmentary longitudinally sectioned view of the assembled pen parts.

The invention generally comprises a transparent barrel 10, a tubular display insert 20, a spring 30, a cartridge 40 and a cap 50.

The barrel is provided with a central bore 12 having an inner shoulder 14 upon which, in the conventional pen, would rest the spring 30. In the present invention however, the tubular display unit 20 is positioned in the bore with an end 22 resting upon the shoulder. The outside diameter of the insert is slightly less than the inside diameter of the bore to permit easy movement of the insert when positioned inside the barrel or when removed therefrom.

The inside diameter of the tubular insert is slightly greater than the diameter of the cartridge, but slightly less than the diameter of the spring. Thus the cartridge moves freely with respect to the tubular insert when propelled or retracted by the mechanism. The spring 30 rests on the remaining end 24 of the tubular insert, encircling the cartridge when inserted into the barrel, and compressing the insert to the shoulder 14 of the barrel at all times. Adjacent the open end 42 of the cartridge, a pair of ears 44 are formed for compressing the spring when the pen is assembled.

2

The cap 50 terminates in a threaded portion 52 which engages the corresponding threaded shank of the barrel. Within the cap is provided an operating mechanism 54 having a push button 56 for propelling the cartridge through the opening 16 against the action of the spring and for releasing the cartridge from the protracted position. The operating mechanism may be of any known construction and is not, per se, the subject of the present invention.

10 The display tubular insert 20 contains the printed or decorative material 26. The material may take the form of printing in a contrasting color on the outside of the insert, or the surface may be decorated or colored in other ways to permit observation through the transparent barrel. The display material may be wrapped around the insert. The insert itself may be an extruded tube sliced to the proper length for use in the pen.

15 The pen is assembled into the form shown in FIG. 2, with the spring mounted on top of the insert and underneath ears 44 formed on the cartridge. The insert has a length extending from the shoulder 14 to the threaded shank of the barrel. This length places the spring within the cap which is made of opaque material to hide the spring from view.

20 The assembly of the parts requires little more than the assembly of the conventional ball point pen. The spring and insert are positioned over the ball point end of the cartridge which is inserted into the barrel with the insert resting on the shoulder 14. The cap is then threaded to the barrel, compressing the spring and completing the assembly.

25 The parts may all be made of molded material with the possible exception of the ball point and spring.

The construction achieves the following advantages:

30 (1) The parts are assembled as easily as they are in the conventional ball point pen,

(2) The parts require no change in the mold used for making the conventional pen parts,

35 (3) The construction is pocketless thus making display changes as easy as possible.

(4) The display material may be changed when desired,

40 (5) The invention may be incorporated within the conventional barrel and cap at minimum cost, and

(6) The display surface is on the inside of the pen where it is protected.

45 I have thus described my invention, but I desire it understood that it is not confined to the particular forms or uses shown and described, the same being merely illustrative, and that the invention may be carried out in other ways without departing from the spirit of my invention, and therefore I claim the right to employ all equivalent instrumentalities coming within the scope of the appended claim, and by means of which objects of my invention are obtained and new results accomplished.

50 I claim:

55 A display ball point pen comprising a hollow barrel having a transparent portion, a cap therefor, a tubular insert for display through the transparent portion of the barrel; a cartridge having a ball point at one end extending through said insert, said barrel having an opening through which the ball point of the cartridge is projected, a shoulder formed within said barrel adjacent said opening, said insert being seated on said shoulder; and a spring

engaging said insert; said cartridge provided with an integral ear engaging and compressing said spring on said insert; and forcing said insert against the seat, said cap removably attached to said barrel and provided with an operating mechanism engaging the end of the cartridge for propelling said cartridge through said opening of the barrel, into writing position against the action of the spring and for releasing the cartridge to a retracted position.
